UNITED STATES PATENT OFFICE.

FREDERICK HAMMOND, OF HOUSTON, TEXAS, ASSIGNOR TO H. F. COHEN.

MASK FOR PRINTING MACHINES.

Application filed May 6, 1924. Serial No. 711,495.

This invention relates to new and useful improvements in a mask for printing machines.

One object of the invention is to provide a printing machine mask of such construction that it will hold the sensitized paper in proper relation to the film, so as to give a correct and uniform margin to the printed picture thus obviating the necessity of trimming the completed picture.

Another object of the invention is to provide a printing machine mask of such construction that the films may be passed through the machine in a strip, and the pictures successively and quickly printed, thus making it unnecessary to cut the strip into individual films for printing purposes.

A further feature of the invention resides in the provision of a very simple type of mask for printing machines by the use of which the printing process may be easily and quickly accomplished.

With the above and other objects in view, this invention has particular relation to certain novel features of construction, operation and arrangement of parts, an example of which is given in this specification, and illustrated in the accompanying drawings, wherein:—

30 Figure 1 is a vertical sectional view of a printing machine, with the mask applied thereto.

Figure 2 shows a horizontal sectional view of the machine showing a plan view of the mask thereon.

Figure 3 shows a plan view of the mask; and,

Figure 4 shows an edge view thereof.

Referring now more particularly to the drawings, wherein like numerals of reference designate similar parts in each of the figures, the numeral 1 designates the casing of the printing machine whose upper side declines forwardly and is provided with the transparent printing table 2. The numeral 3 designates the platen which is suitably mounted by means of the hand operated lever, or handle 4, and the toggle links 5, 5, so that it may be firmly pressed against the paper in printing, and raised therefrom when the printing process has been com-

pleted. In the casing 1 there is a lamp 6, wired in circuit with a suitable battery, or other source of electrical energy, and the electrical circuit is equipped with an automatic switch 7 through which the circuit is completed, the instant the platen presses against the paper and broken simultaneously with the raising of the platen. This obviates all possibility of exposing the paper before or after it is in absolute contact with the negative. The parts of the printing machine hereinbefore described are of conventional construction and are adverted to for the purpose of a clearer understanding of the advantages and method of use of the improved type of mask presently to be described.

This mask is in the form of a rectangular plate 8, preferably of copper, and having the marginal perforations 9, 9, near one edge, to receive the hooks 10, 10, above the table 2, to hold the mask superimposed in proper relation above the table.

The mask also has an opening 11 therethrough, usually rectangular in form, through which the paper is exposed to the light. This opening is of the required size to accommodate the negative, masks with openings of different sizes being used for different sizes of negatives or pictures. Spaced from one side and from one end of the opening are the rib-like abutments 12 and 13, against which the corresponding margins of the print paper 14 abuts, and these abutments hold the paper in proper position over the opening 11, so that the picture, when printed, will be centered on the paper, with a uniform margin, thus dispensing with the necessity of trimming the completed picture.

The strip of films 15 is passed over the table 2, and underneath the mask without obstruction, so that negatives of a continuous strip may be printed successively without the necessity of cutting the strip into individual negatives.

What I claim is:

The combination with a printing machine having a printing table formed with a transparent portion, said machine also being provided with hooks, of a mask adapted to rest

on said table and having an opening adapted to align with said transparent portion, up-standing abutments on the upper surface of the mask, said abutments being arranged in substantially right angular relation to each other and spaced from one side and one end respectively of said opening, said mask hav-

ing perforations through which said hooks are adapted to engage to hold the mask in proper alignment with said transparent portion. 10

In testimony whereof I have signed my name to this specification.

FREDERICK HAMMOND.
